[57] ABSTRACT

The invention relates to a circuit which permits selecting any one of N unique selection intersections with equal probability. The selection intersections comprise a switch matrix with N switches, each switch comprising a selection intersection. The circuit consists of a clock circuit means with a low frequency and a high frequency output, and a counter circuit driven by the output. The counter circuit drives the switch matrix, and the high frequency output is applied to the counter only during a low output of the matrix. The counter has two sets of outputs, each one connected to a different axis of the matrix. Thus, after each count, a different intersection of the matrix is selected. The selected intersection is the one corresponding to the last count.

EQUAL PROBABILITY SELECTION CIRCUIT

BACKGROUND OF THE INVENTION

This invention relates to an electronic selection circuit which is capable of having one or more once selected selection intersections removed from a group of N selection intersections by utilizing electronic circuit means and further is capable of selecting the unremoved selection intersections with equal probability, and in more detailed description, relates to an equal probability selection circuit including a specially controlled electronic clock circuit, a counter circuit driven by the said clock circuit, a switch matrix circuit driven by the said counter circuit having N unique intersecting points corresponding to N unique selection intersections numbered with N unique numbers and having a characteristic which allows removal of any number or all of the N selection intersections, and a feedback circuit driven by the aforesaid switch matrix circuit, all arranged such that the probability of selecting any one of the unremoved selection intersections is equal to the probability of acquiring any other one without regard to the number of selection intersections already removed and also arranged in the form of a single cycle selection system involving the maximum number of selection intersections and where the probability of acquiring any one of the already removed selection intersections is zero.

The object of this invention is to provide an electronic circuit constructed such that it is possible to remove selection intersections once selected so as to reduce the number of possible objects remaining to be selected thereafter and also to make these selections with equal probability, and its main purpose is to obtain a circuit capable of selecting from among N unique selection intersections, consisting of an electronic clock circuit including a minimum time control circuit capable of controlling the minimum operation time of the selection start switch and two clock circuits, where the frequencies of both a high frequency circuit and a low frequency circuit are sufficiently higher than N cycles per second, a counter circuit driven by aforesaid electronic clock circuit and producing a set of N unique predetermined selection intersections, a switch matrix circuit driven by said counter circuit and having N unique intersecting points each corresponding to a unique selection intersection and each numbered with one of N unique numbers having such characteristics which allows removal of $(N-M)$ selection intersections among the N selection intersections, and a feedback circuit driven by said switch matrix circuit, wherein the output of the aforesaid low frequency clock circuit is selected as the output of the above-mentioned electronic clock circuit and allows selection of one of the selection intersections only when predetermined conditions exist, and a feedback control signal can control the aforementioned electronic clock circuit so as to select the output of the above-mentioned high frequency clock circuit as the output of the above-mentioned electronic clock circuit at times when the selection intersection has already been removed in the aforesaid switch matrix circuit, arranged such that the probability of selecting any one of a group of M selection intersections which have not yet been removed is essentially equal to the probability of selecting any other one and additionally such that the $(N-M)$ selection intersec-

tions which have already been removed may not be selected again.

DESCRIPTION OF THE DRAWINGS

Preferred embodiments of the invention will be described hereunder referring to the attached drawings, in which:

FIG. 1 shows a block diagram of the whole circuit in an embodiment of the present invention;

FIG. 2 shows a more detailed block diagram of the electronic clock circuit 1 in FIG. 1;

FIG. 3 shows a wiring diagram of an example of a typical astable multivibrator circuit used in clock circuit A;

FIG. 4 shows the entire circuit diagram of an embodiment of the equal probability selection circuit of the present invention; and

FIG. 5 shows a timing signal diagram of the outputs of each principal circuit as occurs in the case of performing selection using the equal probability selection circuit of the present invention.

DESCRIPTION OF THE EMBODIMENTS SHOWN HEREIN

FIG. 1 shows an entire circuit containing N unique selection intersections in accordance with the present invention. 1 is an electronic clock circuit, its output being connected to a counter circuit 2 and further the counter 2 to a switch matrix circuit 3 and the matrix 3 to a feedback circuit 4 and the feedback circuit 4 to the electronic clock circuit 1. The entire circuit is activated by means of an input control signal 12 from the selection start switch SSW for the purpose of selecting one selection intersection, this selection made possible by a predetermined feedback control signal 14.

FIG. 2 shows a further detailed block diagram of the electronic clock circuit 1.

There are two clock circuits, A and B whose purpose is to allow electronic clock circuit 1 to provide a unit time signal for driving the counter circuit 2, and low frequency clock circuit A consists of an astable multivibrator circuit where the duty cycle (i.e. period/pulse width) and the frequency F_A are determined by the values of two time constants, T_{A1} and T_{A2} .

In this embodiment, F_A is a symmetrical squarewave having a frequency of 1,000 cycles per second. A typical astable multivibrator circuit as used for clock circuit A is shown in FIG. 3. By establishing the values of capacitors C_{A1} and C_{A2} , two time constants, T_{A1} and T_{A2} , are determined and the frequency F_A is determined in this example as 1,000 cycles per second. The high frequency clock circuit B consists of another astable multivibrator circuit similar to clock circuit A where the two time constants, T_{B1} and T_{B2} , are established so as to obtain a frequency F_B fulfilling the condition that $F_B > 2N'F_A$. In this embodiment the frequency F_B is a symmetrical squarewave having a frequency greater than 160,000 cycles per second. Further, both frequencies F_A and F_B are sufficiently greater than N cycles per second.

In other words, even if any number of selection intersections or all N selection intersections are removed, it is feasible to obtain a series of selection intersections in a single cycle having such characteristics as to allow for such removals by setting the relation between frequencies F_A and F_B such that N' pulses of the squarewave output of clock circuit B fall within one

negative pulse (P) of the squarewave output of clock circuit A.

In this embodiment, $N' = 80$ selection intersections are produced in order to make use of a scale-of-5 counter circuit and a scale-of-16 counter circuit combined in matrix form so as to obtain a continuous series of $N = 75$ unique selection intersections by means of not using 5 of the 80 selection intersections. That is, nand gate 26 (FIG. 4) is not used.

Furthermore, since the use of the output of clock circuit B is prohibited during time delay $t_d = 1/F_B$ by means of a misselection prevention circuit 11, the following relationship is obtained:

$$F_B > 2 \times (75+5) \times 1000 = 160,000 \text{ c.p.s.}$$

Clock circuits A and B are connected to a selection circuit 9 whose purpose is such that the output of either clock circuit A or clock circuit B or neither of the outputs of clock circuit A or clock circuit B may be correctly selected by means of the input control signal 12 and the predetermined feedback control signal 14. The selection circuit consists of nand gates 15, 16 and 17 (FIG. 4) with the output of clock circuit A being connected to the input of nand gate 15, the output of clock circuit B being connected to the input of nand gate 16, and the outputs of nand gates 15 and 16 being connected to the input of nand gate 17. In addition, nand gate 17 has the output of an acquisition request memory circuit 8 applied to its input.

Referring again to FIG. 4, when the output of the acquisition request memory circuit 8 is 0, the output of nand gates 15 and 17 are inhibited. That is, the outputs of nand gates 15 and 17 are 1 during this period.

When the output of the acquisition request memory circuit 8 is 1 and the output of resistor R21 is 1, gate 15 is open to the output Aout of clock circuit A. Under these conditions, when the output Aout is 1, the output of nand gate 15 is 0, and when the output Aout is 0, the output of nand gate 15 is 1. During this period the output of nand gate 16 is inhibited; that is its output is 1.

In cases where the output of the acquisition request memory circuit 8 is 1 and the output of resistor R21 is 0, and after the inhibit period $t_d = 1/F_B$ generated by the misselection prevention circuit following the 1 to 0 transition of output Aout, nand gate 16 is open to the output Bout of clock circuit B. At this time, when the output Bout is 1, the output of nand gate 16 is 0, and when the output Bout is 0, the output of nand gate 16 is 1. During this period the output of nand gate 15 is 1.

Nand gate 17 responds only when the output of either nand gate 15 or nand gate 16 is 0. Further, it is obvious that the output of nand gate 17 is in phase with output Aout or Bout of clock circuit A or B depending on which is being selected. Aout and Bout have no particular phase relationship at any time, in other words the signals Aout and Bout are asynchronous.

The misselection prevention circuit 11 is constructed in such a way that a capacitor C_3 is connected between the output of clock circuit A and the input of nand gate 16. Capacitor C_3 is discharged beginning when the output Aout makes a 1 to 0 transition and before the output of nand gate 16 could potentially make a 1 to 0 transition. In other words, the object of this circuit is to prohibit selection of output Bout of clock circuit B as

the output of nand gate 17 during the delay time of approximately $1/F_B$.

A pulse forming circuit 10 is connected to the output of nand gate 15 through capacitor C_2 coupled to the input of inverter 18, the output of which is connected to the input of the acquisition circuit 7. When the output Aout of clock circuit A makes a 0 to 1 transition, the output of nand gate 15 makes a 1 to 0 transition which coupled through capacitor C_2 produces a negative pulse at the input of inverter 18. Thus, the output of inverter 18 provides a positive pulse to the input of the acquisition circuit 7 at the time immediately following a 0 to 1 transition of Aout.

The acquisition circuit 7 consists of nand gate 19, 15 having three terminals on the input side and one terminal on the output side.

After the selection start switch SSW is operated and released the output of inverter 5a of the minimum time control circuit 5 makes a 0 to 1 transition. When and 20 if a selection intersection is selected at the same time or with a slight delay with respect to the 0 to 1 transition of inverter 5a, the output Aout will make a 0 to 1 transition and the output of the pulse forming circuit 10 will be a positive pulse and at this time the output of the 25 acquisition circuit 7 makes a 1 to 0 transition which resets the acquisition request memory circuit 8. In other words, the operation of this circuit 7 is that of a monitor circuit whose purpose is to suspend the output 13 of the above-mentioned selection circuit 9 (i.e. the output 30 of the electronic clock circuit 1) by resetting the said acquisition request memory circuit 8 and thereby suspending further operation of the counter circuit 2 when all the outputs of the inverter 5a, the resistor R21 and the pulse forming circuit 10 are 1. The minimum 35 time control circuit 5 consists of monostable multivibrator circuit comprising nand gate 5b, inverter 5a and capacitor C_1 . The said monostable multivibrator circuit is in a stable condition when the selection start switch SSW is in an ON or 0 condition or ordinarily OFF or 40 1 condition, but a pulse having a fixed pulse width is generated as the output of said minimum time control circuit 5 during the time capacitor C_1 is discharging. This prevents the possible rapid operation of selection 45 start switch SSW from generating a very short pulse at the output of inverter 5a such that it is almost predictable that selection of closely following selection intersections would occur. In other words, the minimum operation time of selection start switch SSW can be controlled. Thus, it becomes feasible to always acquire the 50 aforementioned selection intersection with essentially equal probability without any effect caused by the operating time of the selection start switch SSW.

The inhibit circuit 6 is provided for the purpose of preventing a further selection until the correct switch located at the intersecting point in the switch matrix circuit 3 is operated (i.e. open contacts) corresponding to the selection intersection to be removed. The circuit consists of nand gate 6b and inverter 6a. When the selection start switch SSW is ON or 0 in the process of selecting, the output of nand gate 5b in the minimum time control circuit 5 is 1. Even if an operator who performs selection does not operate (i.e. open contacts) the switch, corresponding to the already selected selection intersection, by mistake and desires to perform selection, the lamps remain lit and the output of inverter 6a is 0 since the output of resistor R21 (i.e. the feedback control signal 14) is 1, thus inhibiting the output of

nand gate 6b (i.e. the output is held at 1). When the operator operates the switch corresponding to the already selected selection intersection, the feedback control signal 14 becomes 0 and the output of inverter 6a becomes 1. Accordingly, the output of nand gate 6b becomes 0 corresponding to the feedback control signal 14 during a time when the selection start switch SSW is ON or 0. The acquisition request memory circuit 8 has the purpose of providing a resettable memory of one bit until the said acquisition request memory circuit 8 is set for the purpose of allowing operation of clock selection circuit 9, and comprises a set/reset flip-flop consisting of nand gate 8a and 8b. It is set such that the output of nand gate 8a becomes a 1 when the output of nand gate 6b is momentarily 0 and is reset so as to obtain a 0 output from nand gate 8a when the output of the acquisition circuit 7 is momentarily 0.

FIG. 4 shows the details of the counter circuit 2. The counter circuit 2 is driven by the electronic clock circuit 1, and consists of counter circuits X and Y constructed by using binary counter stages and decoders DX and DY, and is operated by the output 13 of the aforesaid electronic clock circuit 1. In FIG. 4, the counter circuit X consists of a three stage sequential type binary counter, stages B1, B2 and B3, and the outputs of stages B1 and B3 are connected to the inputs of nand gate 20, the output of which is fed back to reset terminals BR1, BR2 and BR3 of binary counter stages B1, B2 and B3 respectively. Thus a scale-of-5 counter circuit is formed. In other words, five different output combinations are possible so as to correspond to a series of unique selections which are mutually exclusive. The logical value of nand gate 20 is Q1.Q3, and the binary counter stages B1, B2 and B3 are reset at that time only. Here, Q1 and Q3 are the output logical values of the respective binary counter stages B1 and B3.

The nand gates 21 through 25 constitute a decoder DX and usually have an output of 1, but the output being selected at any moment has an output of 0. In FIG. 4, a counter circuit Y consists of four stages of binary counters connected in series B4 through B7, and 16 (i.e. 2^4) output combinations are possible so as to correspond to a series of unique selections which are mutually exclusive, but one combination is not used. Counter circuit Y is connected to the four each input terminals of nand gates 26 through 41, each gate having one output terminal. Nand gate 26 is not used as mentioned above. The output condition of counter circuit Y is similar to the output condition of counter circuit X previously mentioned.

Furthermore, the number of binary counter stages for counter circuits X and Y is appropriately determined depending on the number of selection intersections N desired and the number of stages can be freely increased or decreased. The minimum number of stages is 1, where it is logically possible to obtain $N = 2$.

In another embodiment, it is feasible to obtain N unique selection intersections even though the counter circuit is not constructed in matrix form.

Since the counter circuits X and Y divide the square-wave of the electronic clock selection circuit 1 by 5 and 16 respectively, and a clock pulse is generated by means of a nand gate, they generate one decoder pulse each in such a way that the output pulses of decoders DX and DY are invariably in phase with each other at any one time.

The purpose of switch matrix circuit 3 is to provide memory for selection intersections already removed through selection, and consists of driving transistors TR1 through TR5 and TR6 through TR20, resistors R1 through R5 and R6 through R20, 75 diodes D1 through D75 and 75 switches S1 through S75, being driven by the aforementioned counter circuit 2 where selection intersections are arranged by using one decoder pulse each from decoder DX and decoder DY corresponding to the above-mentioned N' ($N' = 80$ in this embodiment) numbered intersections. Here, since the nand gate 26 is not used as described above, $1 \times 5 = 5$ intersections are not formed as selection intersections, but the feedback control signal 14 is 0 at such times and this causes output Bout to be selected as the output of the electronic clock circuit 1. Thus, $80 - 5 = 75$, namely $N' - 5 = N$ is obtained, and N selection intersections are produced out of N' intersections and are arranged at each point of intersection of the switch matrix circuit 3. Simultaneously, the switch matrix 3 should display which selection intersection is selected by some means such as a visible display using lamps as described in the present embodiment. A light emitting diode may be substituted for each lamp as well. Also, the switch matrix 3 should display whether previously selected selection intersections have been removed or not by some means such as the position (i.e. ON or OFF) of each switch in the matrix as described in the present embodiment. In selection generated by means of coincidence of one decoder pulse from decoder DX at an arbitrary time together with a decoder pulse from decoder DY corresponding to the aforesaid clock pulse, for example, in the case of nand gate 21 and nand gate 40, the current from the power supply B+ flows through lamp DS1, driving transistor TR1, switch S66, diode D66, driving transistor TR19 and lamp DS19 to resistor R21. Thus, a potential difference is produced across resistor R21 and the feedback control signal 14 having a 1 output is fed back to the aforesaid electronic clock circuit 1, because one end of resistor R21 is connected to ground. Diodes D1 through D75 are provided for the purpose of preventing the current from flowing through lamps other than the selected set.

Feedback circuit 4 consists of resistor R21 being driven by the above-mentioned switch matrix circuit 3 and is capable of transferring the memory of removed selection intersections to the electronic clock circuit 1 by means of the feedback control signal 14 such that selection may be feasible only when the output of said resistor R21 is 1 and the output of clock circuit A is in a predetermined output condition having just made a 0 to 1 transition.

A detailed description of the mode of selection according to the equal probability selection circuit of the present invention will be made hereafter.

Initially, all switches S1 through S75 of the switch matrix circuit 3 are ON (i.e. closed contacts), the selection start switch SSW is OFF, the feedback control signal 14 is 1 and the output of the acquisition request memory circuit 8 is 0.

Thus, nand gate 17 is inhibited and the output 13 of the electronic clock circuit 1 has a 1 output having no relationship to outputs Aout and Bout of clock circuits A and B respectively. The current flowing through the selected selection intersection switch is then interrupted by operation of the appropriate switch (i.e. one of S1 through S75) in the switch matrix circuit 3 caus-

ing the feedback control signal to become 0 which causes the output of inverter 6a to become 1 which enables nand gate 6b. Next, when selection start switch SSW is operated ON in order to begin selection of any one of a series of selection intersections of a single cycle consisting of M selection intersections. The acquisition request memory circuit 8 is set which causes its output to change from 0 to 1 and the aforesaid nand gate 17 is enabled. Furthermore, since nand gate 15 is inhibited, selection of squarewave F_A becomes impossible and such a condition allowing selection of squarewave F_B is obtained. Squarewave F_B advances the counter circuit to the point where the next selection intersection not previously removed allows current to flow through resistor R21 causing the feedback control signal 14 to become 1 and thus inhibit nand gate 16 and enable nand gate 15 thereby selecting squarewave F_A as the output 13 of nand gate 17 which is 0 at that time until the end of negative pulse P. This process is repeated many times while selection start switch SSW is held ON. Also, at the end of every negative pulse P when squarewave F_A and the output 13 of nand gate 17 make a 0 to 1 transition, the output of nand gate 15 makes a 1 to 0 transition which causes a positive pulse to appear at the output of inverter 18 through capacitor C2.

Next, depending on the operator, selection start switch SSW is released or placed OFF enabling one input of acquisition circuit 7.

When by means of either F_A or F_B selection, the counter is advanced to a selection intersection not yet deleted causing feedback control signal 14 to become 1, another input of acquisition circuit 7 is enabled. Finally, at the end of negative pulse P, the output of inverter 18 provides a positive pulse fully enabling acquisition circuit 7 such that during the pulse time, the output of nand gate 19 becomes 0 resetting acquisition request memory circuit 8 output to 0 and in turn inhibiting the clock output 13 of clock selection circuit 1 thus completing the single selection cycle wherein a single selection intersection is selected. In other words, a series of selection intersections of a single cycle consisting of M cycles of squarewave Aout of clock circuit A is arranged in such a way that one of M unique selection intersections and the transition from 0 to 1 of Aout correspond to each other in every cycle.

Furthermore, since $F_A = 1000$ c.p.s. and $N' = 80$, $N = 75$ the probability of selecting any one of N selection intersections is substantially $1/N$, where F_A in c.p.s. is sufficiently large with respect to N c.p.s. and also due to the operation of the minimum time control circuit 5, which is equal to the probability of selecting any other one of the N selection intersections and is also essentially independent of the number of selection intersections.

Further, since switches in the switch matrix circuit 3 corresponding to previously removed (N-M) selection intersections are OFF (i.e. open contacts) in the case where M selection intersections have not yet been removed, the current from the power supply B+ does not flow through the intersection point corresponding to the aforesaid selection intersection which has already been removed and the output across resistor R21 (i.e. the feedback control signal 14) is 0. Accordingly, the 1 input of nand gate 15 is changed to 0 and the 0 input of nand gate 16 is changed to 1, thus output Aout is in-

hibited and output Bout is selected as output 13 of the above-mentioned electronic clock circuit 1.

Also, since the frequency of clock circuit B is $F_B > 2N'F_A$, N' cycles of Bout can be contained within the negative pulse portion P of the aforementioned clock circuit A and the 0 to 1 change of the output Aout is still obtained even if any number or totally all N selection intersections have been removed, and it is feasible to select selection intersections in any case. In other words, the switch matrix circuit 3 has such a characteristic that any number or the total number of selection intersections can be removed. Furthermore, the circuit is arranged such that selection is performed independently of the (N-M) selection intersections already removed and the probability of selecting any one selection intersection is $1/M$ which is equal to the probability of selecting any other one, and further, so that the (N-M) selection intersections already removed are prevented from being selected again by means of the feedback control signal 14. Thus, it is feasible according to the present invention to perform selection successively with the same probability of selecting selection intersections numbered with predetermined N unique numbers among those selection intersections which have not yet been removed, and the present invention can be practically applied in the construction of bingo game number selection units as well as having wide application in other fields of equal probability selection.

30 I claim:

1. An equal probability selection circuit allowing the selection of any one of N unique selection intersections with equal probability and comprising:

a selection start switch means;

clock circuit means, driven by said selection start switch, and having a low frequency output and a high frequency output;

counter circuit means, driven by the output of the clock circuit means, and having two sets of outputs;

a switch matrix, comprising N switches each switch comprising a selection intersection; each switch having two terminals, one terminal of each switch being connected to an output from one of the two sets of outputs of the counter circuit; the other terminal of each switch being connected to an output from the other of the two sets of outputs of the counter circuits; and

feedback circuit means receiving an output from said matrix when a selection intersection has been selected and providing, at that time, an output to the clock circuit to inhibit the high frequency output of the clock circuit.

2. A circuit as defined in claim 1 wherein said clock circuit means comprises a high frequency clock to provide said high frequency output and a low frequency clock, to provide said low frequency output; the frequency of said low frequency clock being numerically greater than N;

the high frequency output being numerically greater than $2 \cdot (N) \cdot (\text{low frequency output})$.

3. A circuit as defined in claim 1 and further comprising an acquisition circuit to control the acquisition of a next selection intersection.

4. A circuit as defined in claim 1 and further comprising a misselection prevention circuit means to disconnect the clock circuit means from the counter circuit

means for a delay time of 1/(the high frequency output).

5. A circuit as defined in claim 2 and further comprising a misselection prevention circuit means to disconnect the clock circuit means from the counter circuit means for a delay time of 1/(the high frequency output).

6. A circuit as defined in claim 3 and further comprising a misselection prevention circuit means to disconnect the clock circuit means from the counter circuit means for a delay time of 1/(the high frequency output).

7. A circuit as defined in claim 1 wherein, when a selection intersection is selected, the intersection is removed by opening the switch associated with said intersection, whereby (N-M) intersections may be removed;

the remaining M intersections being selectable with equal probability.

8. A circuit as defined in claim 2 wherein, when a selection intersection is selected, the intersection is removed by opening the switch associated with said intersection, whereby (N-M) intersections may be removed;

the remaining M intersections being selectable with equal probability.

9. A circuit as defined in claim 3 wherein, when a selection intersection is selected, the intersection is removed by opening the switch associated with said intersection, whereby (N-M) intersections may be removed;

the remaining M intersections being selectable with equal probability.

10. A circuit as defined in claim 1 and further com-

prising inhibit circuit means for preventing the further selection of selection intersections until after a previously selected selection intersection, has been removed by opening the contacts of the switch corresponding to the previously selected selection intersection.

11. A circuit as defined in claim 2 and further comprising inhibit circuit means for preventing the further selection of selection intersections until after a previously selected selection intersection, has been removed by opening the contacts of the switch corresponding to the previously selected selection intersection.

12. A circuit as defined in claim 3 and further comprising inhibit circuit means for preventing the further selection of selection intersections until after a previously selected selection intersection, has been removed by opening the contacts of the switch corresponding to the previously selected selection intersection.

13. A circuit as defined in claim 1 wherein one of the two sets of outputs of the counter circuit means comprises n_1 outputs, and wherein the other of the two sets of outputs of the counter circuit means comprises n_2 outputs; and wherein $(n_1)(n_2) > N$.

14. A circuit as defined in claim 2 wherein one of the two sets of outputs of the counter circuit means comprises n_1 outputs, and wherein the other of the two sets of outputs of the counter circuit means comprises n_2 outputs; and wherein $(n_1)(n_2) > N$.

15. A circuit as defined in claim 3 wherein one of the two sets of outputs of the counter circuit means comprises n_1 outputs, and wherein the other of the two sets of outputs of the counter circuit means comprises n_2 outputs; and wherein $(n_1)(n_2) > N$.
